EDWARD B. ALLEN, OF NEWTOWN, CONNECTICUT, ASSIGNOR TO THE SINGER MANUFACTURING COMPANY, OF ELIZABETH, NEW JERSEY, A CORPORATION OF NEW JERSEY.

STITCHED BUTTONHOLE.

Original application filed January 9, 1924, Serial No. 685,101. Divided and this application filed October 9, 1924. Serial No. 742,506.

This invention has for an object to provide a round eye buttonhole with an overseam of substantially uniform width and appearance. As disclosed in my copending application Serial No. 685,101, filed Jan. 9, 1924, of which this application is a division, buttonhole sewing machines are commonly constructed with stitch-forming mechanism and a work-holder with provision for relative movement between them to carry the sewing around the buttonhole-slit. In cloth buttonhole machines the stitch-forming mechanism usually comprises an upper reciprocating and laterally jogging needle which cooperates with suitable under-thread mechanism mounted in a rotary turret. The needle-bar and turret are connected for turning movements in sewing around the eye of the buttonhole. Heretofore it has been the practice to hold the turret of the stitch-forming mechanism in a fixed position with the plane of vibration of the needle normal to the center line or stem of the buttonhole-slit as the sewing progresses along the first side of the buttonhole and the first quarter of the eye; i. e., until the sewing has reached a point even with the center of the circular part of the eye. The stitch-forming mechanism is then rotated 180° as the stitches are laid around the semi-circular second and third quarters of the eye. Rotation of the stitch-forming mechanism is then stopped with the plane of vibration of the needle again normal to the center line of the buttonhole as the sewing progresses along the last quarter of the eye and down the return side of the buttonhole. In other words buttonholes sewn by machines of the prior art have had the stitches laid substantially normal to the center line of the buttonhole along the stem of the buttonhole-slit and the first and last quarters of the eye. Buttonholes having elongated pear-shaped eyes may be satisfactorily sewn in accordance with the practice above outlined while retaining a substantially uniform width of overseam. At least the departure from normal width of overseam is not objectionable along the first and last quarters of the eye. In attempting to shorten the eye of the buttonhole, however, and make it more nearly circular and less pear-shaped, as often demanded by the trade, it

is found that the effective width of the overseam along the first and last quarters of the eye, as sewn in accordance with the customary practice, is so reduced as to contrast unfavorably with the width of the overseam along the buttonhole-slit and around the second and third quarters of the eye. 55

According to the present improvement in its preferred embodiment, as the sewing starts, the plane of vibration of the needle stands normal to the center line of the buttonhole, as heretofore, but provision is made for reversely rotating the stitch-forming mechanism as the sewing approaches the eye of the buttonhole so that when the eye is reached the plane of vibration of the needle stands at such an angle to the center-line of 70 the buttonhole that the initial eye-stitches will be laid more nearly normal to the underlying edge of the eye instead of normal to the center-line of the buttonhole, as heretofore. As soon as the initial eye-forming 75 stitches are laid the stitch-forming mechanism is rotated in the usual direction but for double the angle in excess of 180° that the stitch-forming mechanism was initially reversely rotated. After the final eye-forming 80 stitches are laid the stitch-forming mechanism is reversely rotated during the sewing along the return side of the buttonhole until the plane of vibration of the needle again stands normal to the buttonhole-slit. If the 85 stitch-forming mechanism is reversely rotated as above pointed out, the spacing of the depth stitches will be reduced along the stem portions of the overseam adjacent the initial and final eye-stitches. The effect of 90 this reduction in spacing of the depth stitches is to bunch such stitches at the apex of the angle where the stem and eye stitches meet, thereby forming strong anchorages at these points for holding sharp bends in the 95 cord and thus accentuating the desired circular appearance of the eye. After the sewing is completed, the stitch-forming mechanism is or may be reversely rotated to restore it to initial position ready for the next 100 sewing operation.

In the accompanying drawings, Fig. 1 is a diagrammatic view of the eye end of a buttonhole having the usual pear-shaped eye. Fig. 2 is a similar view of a round eye 105 buttonhole produced in accordance with the

usual practice of laying the eye stitches. Fig. 3 is a diagrammatic view of a round eye buttonhole produced in accordance with the present invention and Fig. 4 is a face view of the corded face of the buttonhole 5 illustrated in Fig. 3.

Referring to Fig. 1, which illustrates diagrammatically the upper or needle-thread side of the usual pear-shaped eye-end of a buttonhole, it will be seen that the dot-and-dash lines which represent the plane of vibration of the needle stand normal to the center line of the buttonhole as the sewing proceeds in the direction of the arrows 10 around the first and last quarters of the eye. This is in accordance with the customary 15 practice. It will be seen that with the extent of vibration of the needle maintained constant, the width of the overseam around the first and last quarters of the eye is not 20 noticeably or objectionably narrowed as compared to the width of the overseam along the stem or around the second and third quarters of the eye.

25 When the length of the eye, however, is reduced and made more nearly circular and less pear-shaped, as shown in Fig. 2, the width of the overseam around the first and last quarters of the eye is noticeably reduced 30 and contrasts unfavorably with the overseamed portions along the stem and around the second and third quarters of the eye, giving the eye as a whole a distorted appearance.

In accordance with the present improvement in its preferred embodiment, Fig. 3, 35 the plane of vibration of the needle stands normal to the center line of the buttonhole from the beginning point *s* along the major portion of the first side of the buttonhole 40 and until the sewing reaches the point *a* close to the eye. From *a* to *b* the stitch-forming mechanism is gradually reversely turned through an angle to say 24° so that when the eye is reached the plane of vibration of the needle will stand more nearly normal to the edge of the eye at the first quarter of the eye of the buttonhole, instead of normal to the center line of the buttonhole, as heretofore. The angular position 45 of the stitch-forming mechanism is retained in sewing from *b* to *d* and then the stitch-forming mechanism is rotated in the normal direction, in sewing around the eye from *d* to *e*, but through an angle of 180° plus 50 double the angle 24° of initial reverse rotation, or 228° in all. From *e* to *f* the angular position of the stitch-forming mechanism is retained and from *f* to *g* the stitch-forming mechanism is again reversely rotated 55 through an angle of 24° to bring the plane of vibration of the needle again normal to the center line of the buttonhole for sewing along the remaining and major portion of the second side of the buttonhole to 60 the ending point *t*.

By providing a buttonhole sewing machine with means for rotating the stitch-forming mechanism in excess of 180° in the manner described, the eye of the buttonhole is given a uniformly overseamed appearance and is of the desired circular shape. 70 The depth stitches from *a* to *b* and *f* to *g* and particularly at the points *b* and *f* are crowded together, Figs. 3 and 4, and form firm anchorage around which the cord *h* 75 is sharply bent to accentuate the desired circular appearance of the eye. It will be understood that the angular amount of reverse rotation of the stitch-forming mechanism, when used, is not critical and that the preferred amount is specified herein in an illustrative and not a limiting sense. 80

The preferred buttonhole may be characterized as including an overseam embracing the cord *h* on one face of the fabric and having a needle-thread disposed in zigzag arrangement on the other face of the fabric. 85 From the point *s* to the point *a*, Fig. 3, the sum of the inner angles *s'* minus the sum of the outer angles *s''* is zero since the stitch-forming mechanism is not rotated in sewing the major portion of the stem of the buttonhole. From *a* to *b* the sum of the inner angles *a'* minus the sum of the outer angles *a''* is a negative angle of 24° since 90 the stitch-forming mechanism is reversely or negatively rotated through an angle of 24° in sewing the stem stitches immediately adjacent the eye. From *b* to *d* there is no rotation of the stitch-forming mechanism 95 and the difference of the sums of the inner and outer angles is again zero. From *d* to *e* the sum of the inner angles *d'* minus the sum of the outer angles *d''* is a positive angle of 228°, and so on to the point *t*, as will be 100 readily understood. The stem end of the buttonhole may, of course, be finished off or barred in any desired manner.

Having thus set forth the nature of the invention, what I claim herein is— 110

A stitched buttonhole comprising a fabric having a buttonhole-slit enlarged at one end to form a short round eye, a cord extending around said slit on one face of the fabric, and a buttonhole overseam embracing said 115 cord and fabric and including a needle-thread disposed in zigzag arrangement on the other face of the fabric, the sum of the inner angles minus the sum of the outer angles defined by said zigzag needle-thread around the eye being a positive angle in 120 excess of 180° and the sum of the inner angles minus the sum of the outer angles along the stem portions being negative angles substantially equal to one-half of 125 said excess.

In testimony whereof, I have signed my name to this specification.
